UNITED STATES PATENT OFFICE.

CHARLES ORLANDO DUTTON, OF LACHINE, CANADA.

FIRE-ESCAPE.

SPECIFICATION forming part of Letters Patent No. 655,923, dated August 14, 1900.

Application filed January 22, 1900. Serial No. 2,402. (No model.)

To all whom it may concern:

Be it known that I, CHARLES ORLANDO DUTTON, a subject of the Queen of Great Britain, residing at Lachine, in the county of 5 Jacques Cartier, in the Province of Quebec, Canada, have invented a new and useful Fire-Escape, of which the following is a specification.

My invention relates to improvements in 10 fire-escapes; and the object of the invention is to provide a permanent and easily-accessible means of escape from a burning building whereby persons may without difficulty or inconvenience reach the ground; and it consists, essentially, of a hollow tower fitted internally with a spiral staircase and preferably self-closing doors leading into the tower from the corridors of the building, the staircase at the lower end leading onto a balcony 15 which is pivotally swung, so that on the release of a bracket on one of its ends the weight of a person will swing that end of the balcony down and release a series of slats forming the floor of the balcony to make a stairway reaching 20 to the ground, the various parts being constructed in detail, as hereinafter more particularly described.

Figure 1 is a perspective view of my fire-escape, showing the tower partly broken away. 30 Fig. 2 is a sectional elevation of my device, showing the balcony in its lowered position in dotted lines. Fig. 3 is a detail of my device for releasing the steps.

In the drawings like letters of reference indicate corresponding parts in each figure.

A is the column or tower, which is built into or forms part of the ordinary wall of the building, preferably standing out somewhat from the walls, so as to form a Doric or other 40 ornamental column. This column or tower is hollow and fitted up internally with a spiral staircase B. A suitable fireproof self-closing door C, opening inwardly to the tower and communicating with the corridor inside the building, is provided on every flat or story. At the lower end of the staircase B the outwardly-swinging spring-door C' makes an exit 45 from the tower A to the balcony E.

The balcony E is pivotally hung in the center on the spindle H' and supported at its two ends by brackets I and J. The spindle H' is fixed in a bracket H, attached to the wall of

the building, and extends through the brackets e⁵ on the lower edges of the balcony, so as to swing freely. The end-supporting bracket J swings as a hinge in the sockets or rings j and is swung back against the wall by means of a rope j', attached to its outer end. The rope j' passes under and over pulleys j² and j³, respectively, and the end is attached to a pin j⁴ on the wall immediately below the pulley j⁵.

The floor of the balcony E for one-half of its length consists of slats e², pivotally swung in the frame e. The bolt f when the balcony 65 is in its ordinary position is held in a square notch g in the upper portion of the quadrant G by means of a spring f². The slat e³, which is connected by means of the rod e⁴ to the slats e², has a slot e⁵ immediately over the 70 bolt f. The projection f' over the bolt f projects slightly above the level of the slat e³, so that a forward movement, effected by the foot of a person or otherwise, of the projection f' in the slot e⁵ will release the bolt f from 75 the square notch g. The bracket J, being removed from under one end of the balcony E, the effect of any person or weight standing on the slat e³ will serve to tilt the balcony, and the quadrant G begins to assume a different 80 position as the balcony E tilts farther, the slat e³ being held horizontal by the person standing thereon. The projection f' being released from the notch g, as the balcony continues to tilt the quadrant G assumes a different 85 position, and the bolt, as aforesaid, falls into the next notch below the square notch g. The notches g' are so arranged as to allow the bolt to slip through them as the balcony is tilting until it reaches the square notch g' at 90 the lower end of the quadrant G, when the bolt again locks itself, but this time in the lower square notch g². It will thus be seen that on the downward movement of this portion of the balcony E the slats e³ and e² will remain 95 in a horizontal position, as the quadrant G is made with a sufficient number of teeth to allow the end of the balcony to reach the ground.

In order to put my device to practical use, a person descending the staircase inside the 100 tower steps onto the balcony and standing on the slat e³ releases the bolt f from the upper notch in the quadrant G by moving the projection f' in its slot and pulling the cord or

chain *j* he moves the support *J* against the wall and the balcony being pivotally swung will from the person's weight begin to overbalance, thereby bringing the bolt *f* into the next notch below, and so on, according as the balcony swings, until the bolt reaches the last notch in the quadrant *G*, where it locks. It will thus be seen that the slats *e*² will always retain the same horizontal position and that as the end of the balcony descends to the ground a convenient staircase is made for the person descending.

What I claim as my invention is—

1. The combination with the tower and staircase, of a pivotally-swung balcony, pivotally-hung slats forming the floor thereof, adapted to form a stairway, a rod connecting said slats, a spring-held bolt having a projection passing through a slot in the first slat, a quadrant under the balcony to engage said bolt, a removable bracket under one end of the balcony and means for removing said supporting-bracket to allow the balcony to tilt, substantially as described.
2. The combination with a spiral staircase and a hollow tower of a pivotally-swung balcony fitted with a floor of pivotally-swung

connected slats adapted to form a stairway when the end of the balcony swings to the ground, a spring-held bolt, a quadrant to receive said spring-held bolt said bolt having square-shaped notches at each end and teeth between to allow the bolt to slip when released from either of the end slats as and for the purpose specified.

3. The combination with a spiral staircase and tower of a pivotally-swung balcony fitted with a floor of pivotally-swung connected slats adapted to form a stairway, a spring-held bolt, having a lug projecting through the first slat a quadrant immediately under the balcony said bolt being adapted to engage the same the stationary bracket and the hinged bracket, a rope attached to the hinged bracket passing under the balcony to the wall in proximity to the tower and suitable guides and fastening for the rope as and for the purpose specified.

Signed at Montreal, Canada, this 8th day of January, 1900.

CHARLES ORLANDO DUTTON.
